(57) **CLAIM**

The ornamental design for a spinning prize wheel, as shown and described.

DESCRIPTION

FIG. 1 is a perspective view of a spinning prize wheel, showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the portion 9 shown in FIG. 1;

FIG. 10 is an enlarged view of the portion 10 shown in FIG. 1;

FIG. 11 is an enlarged view of the portion 11 shown in FIG. 1;

FIG. 12 is an enlarged view of the portion 12 shown in FIG. 1;

FIG. 13 is an enlarged view of the portion 13 shown in FIG. 1;

FIG. 14 is an enlarged view of the portion 14 shown in FIG. 1;

FIG. 15 is an enlarged view of the portion 15 shown in FIG. 2; and

FIG. 16 is an enlarged view of the portion 16 shown in FIG. 2;

FIG. 17 is an enlarged view of the portion 17 shown in FIG. 2; and,

FIG. 18 is an enlarged view of the portion 18 shown in FIG. 2.

The broken lines in the drawings depict the boundaries of the enlarged views of the spinning prize wheel and form no part of the claimed design.
